DREDGER

Arthur C. Crawford, Rodeo, Calif.

Application March 14, 1939, Serial No. 261,785

21 Claims. (Cl. 37—71)

The present invention relates to improvements in dredgers, and has particular reference to dredgers used in gold mining operations, although, of course, it may be used for different purposes.

The principal object of the invention is to provide a dredger that is simple in construction, economic in operation and possesses desirable properties of maneuverability.

A further object of my invention is to provide a dredger in which a number of dredging units may be arranged alongside of one another for operation at different depths or different strata.

Another object of the invention is to provide a dredger which allows different strata of soil or soils of different characters to be readily separated for differentiation in treatment.

A further object of the invention is to provide improved means for shovel operation including particularly, means for effective scraping of bed rock formation, counter-weight means for decreasing power consumption, improved guide means for the shovel, improved automatic flushing means for the shovel and anti-friction means for facilitating radial travel of the shovel with respect to the axis of its swinging motion.

A still further object of the invention is to improve the maneuverability of the dredger by providing means for holding the dredger against opposing currents, means for advancing the dredger, means for laterally shifting the same and means whereby all of these means exert a lifting effect on the front section of the dredger to allow the same to clear obstacles.

A further object of the invention is to place all of the means for maneuvering the dredger at a high elevation whereby danger of damage due to obstacles is minimized.

And finally, it is proposed to provide means in connection with a dredger of the character described for facilitating inspection and sampling of the soils and subsoils to be worked on.

Further objects and advantages of my invention will appear as the specification proceeds.

The preferred form of the invention is illustrated in the accompanying drawings, in which:

Figure 1 shows a side elevation of my dredger with the shovel in position between scooping and ascending operations;

Figure 2, a side elevation of the dredger showing the shovel in position prior to the lowering of the same for scooping operation;

Figure 3, a side elevation of the dredger show-

ing the shovel at the beginning of the scooping operation;

Figure 4, a detail view showing the shovel of Figure 3 in a different adjustment;

Figure 5, a side elevation of the dredger showing the shovel in elevated position ready for discharge;

Figure 6, an enlarged detail view of the shovel and operating mechanism, in side elevation;

Figure 7, a section taken along line 7—7 of Figure 6;

Figure 8, a section taken along line 8—8 of Figure 6;

Figure 9, a plan view of the barge on which the dredging apparatus is supported;

Figure 10, a sectional view taken along line 10—10 of Figure 6;

Figure 11 a sectional detail view taken along line 11—11 of Figure 6;

Figure 12, a schematic view showing in side elevation, a plurality of shovels arranged in co-operative relation alongside of one another.

Figure 13, a schematic plan view of the arrangement shown in Figure 12, and

Figure 14, a side elevation of a caisson used for inspection and sampling, a portion being shown in vertical section.

While I have shown only the preferred form of my invention, I wish to have it understood that various changes or modifications may be made within the scope of the claims attached hereto without departing from the spirit of the invention.

Referring to the drawings in detail, my dredging apparatus is mounted on a barge 1, which may be rectangular in form and preferably consists of a plurality of sections 2, 3 and 4 securely fastened together by any suitable means. A long recess 5 extends centrally into the barge from in front and forms the well in which the dredging apparatus operates.

The barge is made to float on a body of water, such as the river indicated at 6, in an upstream direction. For holding and maneuvering the barge I provide the following apparatus:

A cable 7 is stretched across the river or other body of water at a considerable height and secured to any suitable means not shown in the drawings. The barge has a rear gantry 8 and a front gantry 9 rising therefrom, the rear gantry comprising two spaced and hollow supporting posts 10 and a cross-member 11, while the front gantry comprises the two posts 12 and a cross-member 13.

The front gantry has a pulley 14 secured there-

to by any suitable means, such as the member 15, and the rear gantry has another pulley 16 secured thereto, the latter being arranged at a higher elevation than the former, it being understood that cable 7 is also higher than pulley 14. Both pulleys are arranged over the median line of the barge, although the front pulley is shown slightly off-set in Figure 9 to allow a second pulley underneath the former to be shown.

A cable 17 is secured to the cross-cable 7 by means of a pulley 18 and is guided underneath pulley 14 and over pulley 16 and downward to a suitable winch not shown. This cable holds the barge against the stream and is used for advancing the same. It will be noted that the cable has a lifting effect on the front section of the barge and may be used to raise the latter when obstacles are encountered in the river bed. A stern line 19 is secured to the winch 19' and leads over a pulley secured to the gantry at a high elevation to a suitable anchoring means so as to clear the body of water and possible obstacles and this line serves as a counter brace to the pull of the head line or cable 17.

In dredging operation, it is customary to start at one side of the river and to stepwise advance sidewise across the river until the other side is reached, whereupon the barge is moved forward to repeat the operation in the opposite direction.

For laterally moving the barge, I provide the two cables 20, the front ends of which are suitably anchored near the anchoring points for the cross-cable 7 while intermediate portions are guided over pulleys 21 suitably connected to the front gantry at the elevation of the pulleys 14 and over pulleys 22 associated with the rear gantry at a higher elevation. The rear ends of these cables are secured to suitable winches 23.

The barge supports on its rear section, and at a suitable elevation, a conventional rotary screen 24, slightly inclined, and suitably actuated by pinions 25. The rear end of the screen discharges upon a conventional stacker conveyor 26, and at the front end I provide a sluice channel 27 which discharges the dredged material into the screen.

At the front end of the sluice channel is pivotally mounted the shovelling apparatus comprising the shovel 30, the shovel channel 31 and the channel guide 32. The channel guide is in the form of an elongated rectangular box having a flat bottom 33, vertical sides 34 and inwardly extending flanges 35 projecting from the upper edges of the sides. The upper bottom edge of this box is swingably supported on a stationary shaft 36 arranged at the front end of the sluice channel 27.

The shovel channel 31 is presented in the form of a long trough, rounded at the corners as at 37, and provided with laterally projecting flanges 38 which register with the flanges 35 of the guide when the channel is inside the latter. The channel is sufficiently smaller than the guide to leave space between the flanges and between the bottom members for the anti-friction means shown in Figures 7 and 8.

The latter means are arranged so that the channel is always supported by anti-friction means even if the top of the channel nears the bottom end of the guide. To accomplish this, I provide, near the bottom end of the guide, the roller 39 supported in bearings 40 rising from the bottom of the channel, which latter may be provided with a suitable reinforcing strip 41 riding on the roller between the bearings. I also provide, at the same end of the guide, rollers 42

which are supported in bearings secured to the flanges 35 and contact the flanges 38 of the channel.

At the upper end of the guide I provide differently located anti-friction means, namely two rollers 43 supported on the guide and contacting the corner sections of the channel, and a second set of rollers 44 having bearing in the sides of the guide and riding on the flanges of the channel.

When the upper end of the channel descends below the top end of the guide, the upper rollers of the guide lose contact and I, therefore, substitute rollers 45 and 46 at the upper end of the channel which, upon entering the guide, become active on the bottom and the flanges as shown in the drawings. It will be noted that roller 45 will freely pass between rollers 43 and that rollers 46 will freely pass inside of rollers 44. The bottom of the guide is preferably provided with a reinforcing strip 47 for roller 45 to ride on.

It will thus be seen that anti-friction means are provided for all possible positions of the channel in the guide, the downward travel of the channel in the guide being limited so as to prevent the channel from leaving the guide by registering stops 48 and 49.

The shovel 30, which may be of any suitable construction, is hinged to the bottom edge of the shovel channel, as at 50, and may be held thereto in either fixed relation or with a certain amount of angular play by straps 51. The latter are slotted (see Figure 6) and one end of each strap is secured to an upper portion of the bottom end of the channel by means of a pin 52 which latter may pass through an independent hole in the strap or through the slot itself, because in the latter case, the weight of the shovel holds the pin firmly in the upper end of the slot during the scooping and ascending operation.

The body portion of each strap is secured to the shovel by means of a second pin 53, which may be passed through a registering hole of the strap as shown in Figure 6 to hold the shovel in fixed position, or may be passed through the slot for allowing the shovel to swing further back.

The two relative positions which may thus be obtained are indicated in Figures 3 and 4, both of which show the shovel at the beginning of the scooping operation. The position of Figure 3 is used for normal scooping operations through yielding soil formation whereas the position of Figure 4 is intended for scraping over hard bed rock.

The shovel movement is particularly illustrated in Figures 1-5; Figure 1 showing the shovel in initial position at the front of the barge and substantially on the water level. From this position it is retracted into the position of Figure 2, then dropped into the position of Figure 3, then pulled forward to again reach the position of Figure 1, whereupon it is made to ascend to the dumping position of Figure 5 and again lowered to the position of Figure 1.

The shovel is operated by means of two cables 55 and 56, the former being attached to a cross-member 57 (see Figure 10) stretching across the top of the shovel and the latter being secured to the back of the shovel as at 58. The cable 56 leads directly to a winch 59, and the cable 55 leads over a pulley 60 supported by a yoke or bail 61 and pulley 62 supported in the upper portion of the front gantry, to a winch 63.

The bail 61 is pivotally supported at 64 in coaxial relation to the channel guide 32 so that

on the ascent of the shovel the latter and the pulley 60 move along the same arc.

The bail 61 is connected, through a pair of cables 68 attached thereto, as at 64, and passing over pulleys 65 and 66 on top of the front and rear gantries, to the counterweights 67 which are slideable in the ports 10 of the rear gantry. The weight of the counterweights is such as to almost balance the dead weight of the rising shovel and attendant parts, whereby the power necessary for raising the load is greatly reduced.

The bail only partakes of the ascending and descending movements of the shovel and remains in the position shown in Figure 1 during the scraping or scooping operation. Suitable means are provided, therefore, to hook the shovel to the bail and to release the latter for ascent, as the shovel passes through the station of Figure 1 in an upward direction, and to reverse the connections on the downward travel, the bail being anchored to the barge and the shovel disconnected from the bail.

The means for effecting the desired changes on each passing of the shovel are particularly illustrated in Figures 6, 10 and 11. Figure 10 shows the means for connecting the bail to the barge. The shovel operates in the long front recess of the barge and the inner walls of the latter defining the recess are provided with inwardly projecting ledges 70 which stop the downward progress of the bail below the water level. In the ledges are pivoted hooks adapted to hook over the sides of the bail and the hooks are driven into firm engagement with the bail by ridges 72 forcing the lower ends of the hooks outwardly. On the return movement of the bucket the hooks are disengaged from the bail by means of pins 73 secured to the shovel striking similar pins 74 projecting from the lower ends of the hooks.

Figure 11 shows the means for connecting and disconnecting the shovel and the bail. The former is provided with detents 75 in the sides thereof and the bail carries pivoted bell-crank levers 76 adapted for hooking underneath the detents. On the upward movement the inclined face of the detent pushes aside the levers 76, which immediately upon passing engages with the detent on account of the weight of the horizontal arm 80 of the bell crank lever. This position of engagement is retained in spite of the horizontal arm of the lever passing a pawl 77 pressed against the arm by a spring 78, because the tapered upper face of the arm 80 crowds the pawl away. On the reverse movement of the shovel and the bail, however, the arm 80 strikes the top of the pawl 77 and is thereby made to release the shovel.

It should be observed that the respective engagements and disengagements must be properly timed so that, on the downward travel of the shovel, the bail is locked to the barge before the shovel is disconnected, while on the travel in the reverse direction, the shovel is hooked to the bail before the latter is released from the barge.

The shovel operation of my dredger will be well understood from the foregoing description.

Commencing with the position shown in Figure 1, we will assume that the bail, which, taken by itself, is lighter than the counterweight, is hooked to the barge by hooks 71 and the shovel is pulled forward by cable 55 which passes over the pulley 60 disposed on the bail. As the shovel advances engagement takes place between hook 76 and the detent 75 for securing the shovel to the bail, and immediately thereafter pin 73

crowds pin 74 inwardly for releasing the bail from the barge.

The bail now rises with the shovel to the dumping position of Figure 5, the counterweights doing a large portion of the work and power being required only for lifting the actual load and what little extra weight is required to insure return of the shovel by gravity.

When the dumping position has been reached the material gravitates from the shovel through the channel 31 toward the screen. To aid in emptying the shovel, I provide a semi-cylindrical tank 81 above the shovel which is pivotally suspended from a shaft 82 and is slightly overbalanced to normally return to a position of rest, the heavier side being supported by a plunger 83 slideable in a cylinder 84. As the shovel rises to dumping position, the edge of the shovel strikes the plunger and tilts the heavier end of the tank upward, whereby a load of water contained in the tank is emptied into the shovel and made to aid in flushing the shovel and the shovel channel. It will be understood, of course, that there is considerable water in the shovel as it rises and that the tank will be refilled each time between operations.

After dumping the shovel is allowed to descend and the bail descends with it. In passing through the position of Figure 1, the bail is first secured to the barge by hooks 71 whereupon the shovel is released from the bail by operation of pawl 77.

Next the shovel is pulled upward, in a rearward direction by cable 56 to assume the position of Figure 2 and is then allowed to drop downward into engagement with the river bottom as shown in Figure 3. From this position it is pulled forward by cable 55 to scoop up a load and to return to the position shown in Figure 1.

It will be noted (Figures 3 and 4) that the shovel is provided, at its upper rear edges, with rollers 85. These rollers impinge upon the sides of the bail as the shovel approaches the latter and serve to bring the shovel back to a desired angularity for dumping, when it has been allowed relative freedom of play during the scooping action by adjustment of the straps 51 as shown in Figure 4.

The material is discharged from the shovel in its raised position upon the shovel channel which latter discharges upon the sluice channel 21. This channel feeds the material into the rotary screen 24 which drops the finer material upon a suitable separating means such as a riffle board and discharges the coarser material upon the conveyor 26 for stacking. It is apparent that when material is encountered, such as clay, which carries no precious metal, it may be discharged directly from the sluice channel upon the conveyor without being screened by interposing a trough 86 between the sluice channel and the conveyor.

My dredger construction lends itself very well to the arrangement of a plurality of units in multiple formation. It is often desirable to arrange a plurality of units in side by side relation with shovels operating at different depths so as to progressively attack different strata. Some of these strata may be non-metal bearing and may be discharged directly upon the conveyor while other strata may call for screening and separation.

While the dredger moves stepwise across the stream successive units will thus successively attack different strata, and the material of each

stratum may be thus treated individually without interference of material of different character.

Different units may thus be arranged in side by side relation by coupling a plurality of units such as shown in Figure 9 by suitable anchoring means such as indicated at 87. The shovel channels of these units should be of different lengths so as to cause the shovels to operate at different depths.

Or different shovels may be arranged in side by side relation on a single barge as indicated in Figures 12 and 13. In this form a single barge 88 is shown as having three wells 89 accommodating as many shovel units 90. Figure 12 shows how these units are arranged for operating at different depths, so that each successive shovel operates on a deeper layer of material and takes up dredging where the preceding one lays off.

Figure 14 shows a caisson 91 which may be suitably placed on one side of the barge, as at 92 in Figure 9 for lowering into the river bed by means of a cable 93. This caisson is made in the form of a vertical cylinder having a sharp bottom edge as at 94 adapted to cut into the river bottom and having a rubber flange 95 making a hermetic seal with the river bottom. Water may be pumped out of this caisson through a pipe 96 extending to the bottom thereof, whereupon the river bottom enclosed by the caisson is free for inspection and sampling.

As an additional advantage of my counterweight bail, it might be pointed out that at times the shovel may be called upon to dig into an embankment on its ascent and in that case the bail will urge the shovel into the embankment and will hold the shovel against backing away from the embankment. At the same time the counterweights will act to add power to the forward digging operation.

I claim:

1. In a dredger, a barge, a shovel, means for mounting the same with freedom of scooping action below the barge and of ascending motion toward dumping position, a counterweight, and connecting means between the latter and the shovel, the latter means including means for rendering the counterweight active to aid in lifting the shovel during the ascent, and for retaining the counterweight in an inactive position during the scooping operation.

2. In a dredger, a barge having a front gantry rising therefrom, a shovel, means for swingably mounting the same with freedom of scooping action below the barge and of ascending motion at the front of the barge to dumping position, a cable for actuating the shovel and being guided over the front gantry, and a movable guide for the cable, the latter guide being movable on an arc corresponding substantially to that described by the ascending shovel, a cable having one end connected to the guide and having a counterweight at its other end, and means for training the cable to exert upward pull on the guide, the counterweight being sufficiently heavy to overbalance the weight of the guide when the latter is in substantially horizontal position.

3. In a dredger, a shovel, a shovel channel supporting the same, means for moving the shovel to scoop up a load and to ascend to dumping position for discharging the load on the shovel channel, a water tank mounted at the point of discharge, and means actuated by the ascending shovel for discharging water from the tank upon the shovel for flushing the latter.

4. In a dredger, a shovel, a shovel channel

supporting the same, means for moving the shovel to scoop up a load and to ascend to dumping position for discharging the load on the shovel channel, a water tank tiltably mounted at the point of discharge and means actuated by the ascending shovel for tilting the tank whereby the latter is made to discharge the water into the shovel for flushing the load into the shovel channel.

5. In a dredger, a tilttable guide, a shovel channel slidable thereon, a shovel connected to the channel, means for operating the shovel for dredging operations and a bail coacting with the shovel, the bail being swingably mounted in coaxial relation to the guide.

6. A dredger comprising a barge having a plurality of recesses extending from the front edge into the body thereof, a shovel for each recess and swingable shovel-operating means movable in the recesses in parallel planes for scooping action of the shovels underneath the barge in parallel lanes, the recesses being of different lengths and the shovel-operating means being correspondingly constructed for operation at different depths, whereby the shovels are made to operate on lanes of progressively increasing depth and whereby the stratum operated on by each shovel is kept separate from the strata operated on by the other shovels for separate treatment if desired.

7. In a dredger, a tilttable guide, a shovel channel slidable therein, the guide and the channel having spaced confronting bottom faces and spaced confronting lateral flanges, anti-friction bearing members supported by each end of the guide in said spaces between the bottom faces and between the flanges, and anti-friction bearing members supported on the extreme end of the shovel channel, the latter bearing members being positioned to clear the bearing members on the corresponding end of the guide when the said end of the channel enters into the guide.

8. In a dredger, a tilttable guide, a shovel channel slidable therein, the guide and the channel having spaced confronting bottom faces and spaced confronting lateral flanges, anti-friction bearing members supported by each end of the guide in said spaces between the bottom faces and between the flanges, and anti-friction bearing members supported on the extreme end of the shovel channel, the latter bearing members being positioned to clear the bearing members on the corresponding end of the guide when the said end of the channel enters into the guide, the extreme end of the channel and the opposite end of the guide having registering stops for limiting the movement of the channel in the guide.

9. In a dredger, a shovel channel, a shovel, means for pivotally securing the bottom of the shovel to the bottom of the shovel channel, a strap, means for pivotally securing the same to the channel at a higher point, and means for securing the strap to the shovel either fixedly or with a limited amount of play.

10. In a dredger, a shovel channel, a shovel, means for pivotally securing the bottom of the shovel to the bottom of the shovel channel, a strap, means for pivotally securing the same to the channel at a point higher than the bottom thereof, and means for securing the strap to the shovel with a limited amount of play.

11. In a dredger, a shovel channel, means for mounting the same with freedom of swinging movement, a shovel, means for pivotally secur-

ing the same to the bottom of the shovel channel, a strap, means for pivotally securing the same to the channel at a point higher than the bottom, means for securing the strap to the shovel with a limited amount of play between normal and retracted positions, and means outside the shovel and the shovel channel for returning the shovel from a retracted to a normal position during a swinging movement of the channel.

12. In a dredger, a barge, a shovel, means for swingably mounting the shovel with freedom of scooping action and of ascending motion toward dumping position, a bail, means for swingably mounting the same to describe an arc corresponding substantially to that described by the ascending shovel, a cable for actuating the shovel being guided to pass over the bail, and means for locking the bail to the barge prior to the scooping operation.

13. In a dredger, a barge, a shovel, means for swingably mounting the shovel with freedom of scooping action and of ascending motion toward dumping position, a bail, means for swingably mounting the same to describe an arc corresponding substantially to that described by the ascending shovel, a cable for actuating the shovel being guided to pass over the bail, means for locking the bail to the barge prior to the scooping operation, and means for hooking the shovel to the bail after the scooping operation and for simultaneously freeing the bail for ascent with the shovel.

14. In a dredger, a barge, a shovel, means for swingably mounting the shovel with freedom of scooping action and of ascending motion toward dumping position, a bail, means for swingably mounting the same to describe an arc corresponding substantially to that described by the ascending shovel, a cable for actuating the shovel being guided to pass over the bail, and means for hooking the shovel to the bail, whereby a lifting effect brought to bear on the bail is transmitted to the shovel.

15. In a dredger, a tiltable guide, a shovel channel confined therein with freedom of sliding movement between positions of full engagement and positions of partial engagement, anti-friction bearing means carried by the guide and supporting the channel in spaced and parallel relation to the entire wall of the guide when the guide and the shovel channel are in full engagement, and additional anti-friction bearing means carried by the end of the channel for sustaining the latter in the same relationship during partial engagement.

16. In a dredger, a barge, a bail, means for

swingably supporting the latter on the barge, means for detachably securing the free end of the bail to the barge, a gantry rising from the barge in the proximity of the securing means, a second gantry rising from the barge in spaced relation to the former, a counterweight and a flexible connection between the bail and the counterweight, the said connection being guided over the gantries for causing the counterweight to exert a lifting effect on the bail.

17. In a dredger, a barge, a bail, means for swingably supporting the latter over an intermediate section of the barge, means for detachably securing the free end of the bail to the front edge of the barge, a gantry rising from said front edge, a second gantry rising from the rear edge of the barge, a counterweight, and a flexible connection between the bail and the counterweight, the said connection being guided over the gantries for causing the counterweight to have a lifting effect on the bail.

18. In a dredger, a barge, a bail, means for swingably supporting the latter on the former, means for detachably securing the free end of the bail to the barge, a shovel, and means for guiding the latter past the securing means, the shovel having means for attaching itself to the bail and for freeing the bail from the barge.

19. In a dredger, a shovel channel, a shovel having hinged connection with the shovel channel, a strap pivoted to the shovel channel and having a pin hole and a slot therein and a pin for securing the strap to the shovel, the pin being engageable with the shovel through the pin hole or the slot in the strap for securing the shovel to the channel in a position of fixed relationship or with limited freedom of angular play.

20. In a dredger, a barge, a bail, means for swingably supporting the latter on the barge, a counterweight, a connection between the counterweight and the bail arranged and adapted to pull the bail upwardly from a downwardly inclined position, and means on the barge automatically engaging the bail for holding the same against the weight of the counterweight when the bail is moved to a downwardly inclined position.

21. A dredge comprising a barge having a superstructure, a dipper mounted on said superstructure to swing from a lower position into an upper discharging position, means for ejecting water into said dipper in said upper position, and means actuated by said dipper for controlling the operation of said ejecting means.
